UNITED STATES PATENT OFFICE

GEORGE W. BYARS, OF LEXINGTON, NORTH CAROLINA

WINDOW SCREEN

Application filed July 5, 1929. Serial No. 376,186.

This invention relates to window screens, and more particularly to roller screens which may be located in the frame of a window at the top of the frame or at the bottom of the frame as may be desired, and is operable between the side members of the window frame, and which may be operated either in conjunction with the raising or lowering of the window or independently of the window as may be desired.

Another very important object of the invention is to provide a roller screen of the character mentioned which when in a roll in operative position will be concealed when the window is in a raised or lowered position dependent upon which end of the window casing my invention may be associated therewith.

Another very important object of this invention is the provision of a screen of this nature which may be readily and easily operatively connected with the sliding window, so that said screen may be moved into and out of operative position during the raising or lowering of the window or when desired may be raised or lowered independently of the movement of the window.

Another very important object of this invention is the provision of a screen of this nature, which is very simple in construction, economical, positive in operation, efficient, thoroughly reliable and practical, and otherwise well adapted for the purpose designed.

Other objects and advantages of the invention will become apparent from a study of the following description, taken in connection with the accompanying drawings, wherein:

Figure 1 is a front elevation of a sliding window and frame therefor and fully illustrating the application of my invention thereto, certain parts of the window frame being broken away for illustrating the operating means for the screen.

Figure 2 is a vertical longitudinal sectional view therethrough.

Figure 3 is a fragmentary detail perspective view of my improved screen structure.

Figure 4 is an elevational view of the roller bracket.

With reference more in detail to the draw-

ing, it will be observed that a window frame for sliding windows is designated generally by the reference character A and that the same embodies a sill 5 from which rise in spaced parallelism the side members 6-6 of the frame, said members being connected at their upper ends through the medium of the top cross frame member 7. As illustrated, the side members 6-6 are preferably of hollow construction, and the inner opposed faces thereof being suitably channeled for the reception of the sliding window section 8-8 therebetween.

Such is the conventional structure of windows of this type and form no part of my invention. In accord with my invention, the inner opposed faces of the respective frame side members 6-6 terminate at their lower ends in spaced relation to the surface of the sill as at 8'-8'. This of course, permits access to be had to the interior of the said hollow frame side members.

My improved screen, designated generally by the reference character B embodies a roller 9, the opposite ends of which extend into the lower ends of the respective side frame members 6-6 in spaced relation to the lower end of the inner faces of these said frame members, and which is suitably supported within the frame members 6-6 at the bottom of the members in bearing brackets 10-10. As shown, the bearing brackets are of substantially U-shaped formation, the legs of the brackets being secured to the rear wall of the side hollow frame members 6-6, the crown portion of the brackets being disposed longitudinally and are provided each with an elongated slot 10' as shown to advantage in Figure 4. At its opposite ends the roller 9 is provided with suitable stub shafts 11-11 journalled within the slots of the respective brackets, said stub shafts being movable longitudinally of the slot, the roller being rotatably supported between said brackets. A

coil spring 6 has one end thereof secured to the respective stub shaft 11 and the opposite ends of the coil spring are secured to the lower legs of the respective brackets as clearly suggested in Figure 1. These springs exert a downward pull upon the respective ends

of the roller 9, acting as a tensioning means for the roller for maintaining the flexible members 19 and the wire screen 12 tightly wound upon the roller, the spring further 5 acting as an equalizer as the screen is rolled and unrolled.

The relation between the roller 9, the screen 12, and flexible members 19 will be herein-after more specifically described.

10 Wound upon this roller and adapted for movement between the inner opposed faces of the members 6—6 is screening material 12 of suitable length and width. This screening material 12 may be of any foraminous 15 material such as wire mesh, or other like materials used in the manufacture of screens. The material 12 has of course one end thereof fixed in any suitable manner to the intermediate portion of the roller 9, the opposite or 20 free ends of the screen having secured thereto and extending for the full width of the screen a suitable stiffening material 13. This stiffening member 13 may be in the nature of a substantially U-shaped elongated strip 25 of metal between the legs of which the said end of the screen may be clenched or otherwise secured therebetween.

To provide suitable guide means for the screen, each of the frame members 6—6 have 30 their inner opposed faces provided with oppositely disposed grooves 14, said grooves extending upwardly from the lower end, of the respective inner faces of the said members to terminate at a point intermediate the ends 35 of the frame members. The opposite longitudinal edges of the screen material 12 are receivable in the respective grooves, as is also the opposite end of the stiffening member 13, in this manner there being provided a neat 40 and tight fit between the frame of the window and the screen, it being intended to permit of course, the sliding movement of the screen between the said side members of the frame.

On the inner face thereof and intermediate 45 its ends the stiffening edge member 13 is provided with a suitable handle or finger grip 16, whereby one may conveniently actuate the same for raising or lowering the screen. At a point substantially intermediate there- 50 in, the frame member 6—6 have their inner faces provided with recesses 17—17. These slots are preferably located adjacent the top or terminus of the grooves 14.

55 Rotatably supported within the side frame members 6—6 and adjacent the opening 17—17 are suitable pulleys 18—18. Flexible members 19—19, of suitable length, said members being in the nature of cords, ropes, or like materials are adapted to be wound upon 60 the roller 9 at opposite ends of the roller, said flexible members 19 having one end thereof secured to the roller, the members 19 then extending upwardly through the hollow frame members 6—6 and are trained over the pulleys 65 18—18. The flexible cords 19 extend through

the openings 17—17 and have their opposite ends fixed to the adjacent end of the stiffened edge 13 of the screen in any suitable manner as at 20.

Assuming that the roller 9 is journaled in the lower end of the frame A or adjacent the sill 5, as illustrated in the drawings, it will be seen that by unwinding the screen 12 from the roller the flexible members 19 will wind themselves about the roller 9 since obviously the roller 9 will be rotated in one direction during the unwinding of the screen 12 thereon. The winding of the members 19 will of course continue until the screen 12 has been unwound to extend upwardly in the frame to about the lower cross member of the window section which has been raised to an open position, the screen enclosing the opening as is illustrated.

Conversely, when the screen is moved downwardly to be wound upon the roller 9, the members 19 will unwind to move downwardly in the groove 14, obviously such being the result since the members 19 have one end thereof connected with the stiffening member 13 as illustrated and described. In this manner the grooves 14 also act as a guide for the flexible members 19. Obviously, also such unwinding of the members 19 will actuate the roller 9 so as to permit the winding of the wire screen 12 thereabout.

From the foregoing description, it will be appreciated that this screen is adapted to be actuated independently of the window section 8—8. However to afford a connection between the stiffened edge of the screen and the adjacent frame member of one of the window sections 8, in the embodiment illustrated, the connection being between the outer window section 8 and the screen, there is provided in the lower face in the window sash, or bottom cross member of the window a groove 21 extending from one end to the other of the sash. This groove is of sufficient width as to receive the outer edge of the stiffening member 13, said member fitting snugly within the groove, so that when the window section 18 is in a lowered or closed position one may raise the window and also unwind the screen upon its roller merely by gripping the handle or finger grip 16 and pushing upwardly as would be the case in the ordinary operation of opening a window of this type.

To close the window, and consequently 120 wind the screen upon its roller, it would be necessary but to press downwardly upon the window 8 for urging the same downwardly in the frame to a closed position as is also the case in the ordinary manner of closing 125 windows of this type.

From the foregoing it will be seen that I have provided an improved roller screen for association with sliding windows which is very simple in construction, economical, posi- 130

tive in operation, and which may be so incorporated in the window structure as to be operated either simultaneously with or independently of the window for moving the screen into or out of operative position.

Even though I have herein shown and described the preferred embodiment of my invention, it is to be understood that the same is susceptible to changes fully comprehensive of the spirit of the invention, and the scope of the appended claims.

Having thus described my invention, what I claim as new is:

1. In combination, a window embodying a frame and a window section slideable in the frame, a pair of oppositely disposed brackets secured to the side members of the frame and adjacent one end of the frame, said brackets being of substantially U-shaped formation, means for securing the legs of the brackets to the frame, said brackets having the crown portion thereof provided with a longitudinally extending slot, a roller having its ends slidably and rotatably supported in the slots of said brackets, springs secured to the brackets and acting upon the ends of said roller respectively, screening material wound about the roller and movable between the side members of the frame, one end of said screening material being fixed to said roller, and a flexible connection between the opposite end of said screening material and said roller for imparting rotary motion to the roller during the winding or unwinding of the screening material thereupon.

2. In combination, a frame, a pair of oppositely disposed brackets secured to the side members of the frame adjacent one end of the frame, each of said brackets comprising a vertically disposed portion having a longitudinally extending slot therein, a roller having the ends thereof slidably and rotatably receivable in the slots of said bracket, a screen windable on the roller and having one end rigidly secured thereto, a flexible member secured at one end to the free end of the screen and having its other end secured to an adjacent end of said roller, said flexible element being windable on said end of the roller, for imparting rotation to the roller during winding or unwinding of the screening material thereupon, springs normally urging the roller toward the adjacent end of the frame, and a roller mounted on the frame, over which said flexible member is trained.

3. In combination, a roller, a flexible screen member windable on the roller, a pair of brackets, said brackets adapted to be secured to a support, each of said brackets including a vertically disposed portion having an elongated slot formed therein for respectively receiving the ends of the roller, springs engaging the ends of the roller and the brackets respectively normally urging the ends of the roller to one end of the slot, and a flexible

member trained over said roller and secured at one end to the free end of the flexible screen member, a pulley over which the second mentioned flexible member is adapted to be trained, and means for rotatably mounting 70 said pulley to the support remote from said bracket.

In testimony whereof I affix my signature.

GEORGE W. BYARS.
